vale, Pa., a corporation of Pennsylvania

Application June 22, 1931, Serial No. 545,917

8 Claims. (Cl. 177—311)

This invention relates to control systems, and, although it has been primarily designed for employment in connection with brake-control means on trains, its utility is by no means to be limited to such function as it is susceptible of use in other fields.

The main object and feature of the invention is the provision of means for testing or indicating the integrity of one or more circuits that control normally deenergized translating means without, however, energizing said translating means when testing the circuit or circuits.

In the accompanying drawings the invention is disclosed in several concrete and preferred forms, in which

Fig. 1 is a diagrammatic view of the circuits constituting one form of the invention; and

Fig. 2 is a view similar to Fig. 1 but showing a more elaborate form of the invention.

In the exemplification shown in the drawings, there are two circuits which here have one path in common, said path being conveniently indicated by conductor C, reference characters A and B indicating line wires which in conjunction with common path C and other devices to be presently described constitute two line circuits. These line circuits may be conceived as extending from a control station D to a remote station E, and in the present instance said control station is one of a plurality of cars, such as the cab of the engine, and said remote station is another one of a plurality of cars, such as the caboose of a train. Any number of intervening cars may, of course, be present, and it will be seen that the line circuits extend from car to car. M¹ indicates a translating device, here a traffic-controlling device such as a brake-control magnet, connected across conductors A and C. M² indicates a similar translating device connected across conductors B and C. M¹ and M² are of the type of brake-control means that are normally deenergized, and which when energized apply the brakes. Any suitable means may be provided to energize M¹ and M². In the present instance is shown a source of direct current O having one lead o¹ connected to path C and the other lead o² connected through wires o³ and o⁴ to either one or both of line conductors B and A. The arrangement is here such that when the engineer's brake valve V is in the position shown in the drawings, that is in release, running or holding position, the contacts are open and no current is supplied to the line wires, but that when valve V is moved to bring contacts v¹, v² and v⁵ into engagement with contacts v³, v⁴ and

v⁶, current is supplied to both M¹ and M² to thereby energize them and give a service application of the brakes. When valve V is moved into an intermediate or lap position in which contacts v¹ and v² are in engagement with contacts v³ and v⁴ but in which contacts v⁵ and v⁶ are out of engagement, M² only is energized whereby the brake application already made is maintained.

It will be understood that with such construction it is desirable to provide means for testing the integrity of the line conductors so that the engineer may be assured at all times that the brakes will function if operated. Also, on long freight trains, it is desirable that the crew in the caboose be kept informed as to the dependability of the brakes.

Accordingly, the following means, or their equivalent, are provided to test the integrity of the line circuit:

Referring first to Fig. 1, the three line conductors (A, B and C) are connected in multiple by a cross conductor 7—8 at the control station and by a similar cross conductor 12—13 at the remote station, and provision is made whereby these elements constitute an unbalanced Wheatstone bridge. This provision here consists in locating two relays G and H in the cross conductors aforesaid, each of said relays having two windings of unequal impedance, said windings being denoted respectively by MM, NN, PP and RR. These windings are reversely arranged, when considering the direction of the flow of current, with respect to each other, so that if current flows in a given and the same direction, at the same time, through both 7—8 and 12—13, said current will encounter high impedance MM first in one cross conductor and low impedance PP first in the other cross conductor, and conversely, when flowing in the other direction it will encounter low impedance NN first in one cross conductor and high impedance RR first in the other conductor. In either event, the result is that points OO and QQ in the two cross conductors will be at different potential and consequently current will flow over conductor C, which latter as will be noted, extends from OO to QQ. The means to supply a testing current, of a character different from that supplied by source O consists here of a transformer T, the secondary of which is included in a circuit composed of the secondary of transformer T, wire 6, cross conductor 7—8 and relay G, wire 9 and wire 10 back to secondary of transformer T. It will now be understood that when current flows over said circuit through re-

lay G it will also flow in the same direction through relay H via line wires A and B, and that current will likewise flow over line wire C to equalize the potential at points OO and QQ. The primary of transformer T is included in a supply circuit consisting here of generator AC, wire 1, primary of transformer T, wire 2, switch S and wire 5 back to AC, and it will be understood that, when S is closed, current will flow from AC to energize primary of transformer T. Any suitable indication means may be employed to denote the integrity or lack of integrity of the line wires, but in the present instance signals are located both in the locomotive and the caboose and furthermore means are provided to control the supply of current from source AC. As here represented, a shunt is arranged around switch S, said shunt here consisting of wire 31, circuit closer 32, wire 33, circuit closer 34 and wire 35. Circuit closer 32 is controlled by relay G which is of the type that requires both of its windings to be effectively energized to enable it to pick up said circuit closer or armature 32. Circuit closer or armature 34 is controlled by slow acting D. C. relay D¹ interposed in conductor C and supplied with current by rectifier J. It will be understood, however, that said shunt around S is by no means essential when other indication means are provided. Such other indication means here take the form of lamps I¹ and I² which are interposed in conductor C, the continuity of said conductor being controlled by an armature or circuit closer 19 controlled by relay H, which latter is of the type that requires both of its windings to be effectively energized to enable it to pick up its armature. It will likewise be understood that signals I¹ and I² are not essential if the shunt around switch S is provided, but it will likewise be understood that both the shunt and the signals may be used to advantage.

Suitable blocking or filtering means, such as are well known in the art, may be inserted in the various leads to separate the current of source O from that of transformer T. In the present instance condensers C¹, C², C³, and C⁴ are inserted in the cross conductors, and are of such capacity as to cause series resonance in the circuit means at the particular frequency of alternating current used. Condenser C⁵ inserted in wire 10 is also a blocking means for the direct current, but in addition has the function of preventing current from reaching a high value if conductors A and B become short-circuited. 16 indicates choke coils interposed in the leads from source O, and magnets M¹ and M² have a very high impedance to prevent flow of alternating current therethrough.

To start the system in operation, switch S is closed thereby energizing transformer T, and current from the secondary of the latter will now flow over wire 6, through cross conductors 1-8 and relay G, over wires 9 and 10 back to secondary. Current will also flow from secondary of T over wire 6, conductor A, cross conductors 12-13 and relay H, conductor B and wires 9 and 10 back to secondary of T. Energization of relays G and H will lift armatures 32 and 19, armature 32 closing the shunt over switch S at one point, and armature 19 closing the connection through conductor C. Current will now flow over conductor C and will light signals I¹ and I², and will, by means of rectifier J, energize slow-acting relay D¹ thereby raising armature 34 and closing the shunt around switch S, which switch may now be opened manually.

The effect of various failures in the integrity of the system will now be considered.

If conductor A is open, say at U, current from secondary of transformer T will continue to flow through relay G but will cease to flow through winding PP of relay H. Relay H therefore becomes deenergized and armature 19 will drop thereby rupturing the circuit through C, which, in turn, extinguishes lights I¹ and I² and after a predetermined period deenergizes relay D¹ there- 10 by dropping armature 34. The dropping of armature 34 ruptures the shunt around switch S and cuts off supply of current from AC to T, thereby deenergizing relay G and causing its armature 32 to drop. The system is now out of operation, but 15 has given indication both on the engine and in the caboose of its inoperativeness.

If conductor B is open, say at U¹, winding RR will receive no current, relay H will become deenergized sufficiently to drop armature 19 and the 20 same results as those previously described will take place.

If conductor C is open, say at U², current will cease to flow therein, lights I¹ and I² will become extinguished and after a predetermined period re- 25 lay D¹ will become deenergized, thereby dropping armature 34 and opening the shunt around S. This, in turn, will cut off current from AC to T, relays G and H will become deenergized, and armatures 32 and 19 will drop. 30

If conductors A and C are short-circuited, say at U and U², current from secondary of T will flow over wire 6, conductor A, short circuit U and U², conductor C, winding NN of relay G, conductor 8, and wires 9 and 10 back to secondary of trans- 35 former T. As both windings of G are not en- ergized, armature 32 will drop thereby cutting off supply of current from AC to T and so rendering the system inoperative, lights I¹ and I² being ex- tinguished and armature 34 dropping after a pre- 40 determined period.

If conductors B and C are short-circuited, say at the points U¹ and U², current will flow from secondary of transformer T through winding MM of relay G, along conductor C, short circuit U¹ and 45 U², conductor B and wires 9 and 10 back to second- ary of transformer T. Therefore, armature 32 will drop with the results previously described.

If conductors A and B are short-circuited, say at U and U¹, a very low impedance path is cre- 50 ated in consequence of which relay G will not re- ceive sufficient current to hold up armature 32, which latter therefore drops with the resultant effect previously set forth.

If either condenser C¹ or C² becomes "shorted" 55 relay G is detuned from resonance to such an ex- tent that it drops its armature 32. The result of this has already been explained. If either con- denser C³ or C⁴ is "shorted", relay H is detuned 60 from resonance and drops armature 19. Lights I¹ and I² are therefore extinguished and, after an interval of time, relay D¹ becomes deenergized and drops its armature 34 thereby opening the circuit between AC and T. The remaining steps need 65 not be repeated here.

X and Y indicate keys in conductor C, of which keys there may be any number. It will be under- 70 stood that by opening and closing any one of said keys according to a prearranged code, signaling may be effected between the stations or between an intermediate point and both stations. Mo- mentary opening of a key such as X or Y will extinguish indication lamps I¹ and I² because cur- rent will no longer flow in conductor C, but, 75

owing to the fact that D^1 is a slow-release relay, it will not drop its armature 34 (unless the key is kept open long enough to consume the retardation period of D^1) and the remainder of the circuits therefore is unaffected.

It will be seen from the foregoing that the system described is relatively simple and constitutes a safeguard whereby failure in integrity of the line conductors will be revealed at one or both ends of the line and at any intermediate point if so desired. The use of a rectifier in the system to supply relay D^1 with current needs perhaps some additional consideration. It will be remembered that, when a short-circuit occurs between line conductors A and C or B and C, a low impedance shunt is established around one or the other of the windings of relay G, and attention is called to the fact that this low impedance shunt passes through rectifier J. Thus, if the short circuit is between A and C, current from T instead of passing through winding MM of G will pass from A to C (say at U^1 and U^2) and will then flow along conductor C through lamp I^1 , rectifier J and relay D^1 to point OO, winding NN, and thence by wires 8, 9 and 10 back to secondary of T. If the short-circuit is between B and C, current from T will pass through winding MM to point OO, thence through relay D^1 , rectifier J and lamp I^1 by way of conductor C, from C to B (say at U^2 and U^1) and thence by wires 9 and 10 back to secondary of T. If the rectifier be of the copper oxide type, its ohmic resistance may increase with age, and, should this happen, the impedance intended to shunt one of the windings of relay G may be too high to cause said relay G to drop its armature. Consequently the short-circuit of the line conductors would not be detected. This condition can easily be cured by arranging light I^1 and rectifier J in multiple instead of in series and by making light I^1 of low resistance as will be apparent, because in that case the low impedance shunt would be through the light and not through the rectifier and an increase in the ohmic resistance of rectifier J would therefore be immaterial. Such an arrangement would, however, have a disadvantage in that if indicator light I^1 becomes open under normal conditions the system would still remain operative but the engineman would receive what might be called a false danger indication by the extinguishing of the light.

In order to avoid all of these disadvantages, the arrangement disclosed in Fig. 2 is proposed. Fig. 2 shows basically an arrangement exactly like the disclosure in Fig. 1 but with certain additions. In view of the close similarity of the arrangement shown in Figs. 1 and 2 it is unnecessary to repeat the description of the system as a whole, and only the additional elements employed in Fig. 2 and their effect upon the system will be pointed out. Briefly, the additional elements consist of two low impedance paths, from conductor C, that shunt the windings of relay H, said paths being controlled by armatures of relay H and by armatures of an additional relay inserted in conductor C. To be specific: K indicates a rectifier and E^1 a D. C. slow-release relay connected in series with light I^2 between key Y and armature 19. 24 is an armature of relay E^1 which when in its up-position closes the break between wires 25 and 23. 27 is a similar armature which in its up-position closes a break between wires 25 and 28. 22 is an armature, controlled by relay H, that in its down-position engages a back contact to close the break between wires 23 and 21, the latter of which is

connected to wire 12. So likewise 29 is a second armature, under the control of relay H, that in its down position engages a back contact to close the break between wires 28 and 30, the latter of which is connected to wire 13. It will now be seen that, when the system is operating normally, relay H is energized and armatures 22 and 29 are up and the two low impedance paths from C are therefore open. Relay E^1 being also energized, armatures 24 and 27 are in the up or 10 closed position. Under normal conditions the system of Fig. 2 will operate exactly as described in connection with the system of Fig. 1, except that an additional rectifier (K) and an additional relay (E^1) are energized. However, when the integrity of the circuits fails, a somewhat different current flow from that described in connection with Fig. 1 takes place in the arrangement of Fig. 2.

Taking up first the condition of a break in conductor A, say at point U, it will be evident that winding PP of relay H will not be energized. As a result of this, armature 19 drops opening the normal path to C, and armatures 22 and 29 likewise drop thereby closing the low impedance 25 paths to C. Current from the secondary of transformer T will, however, flow through the windings of relay G, and in addition current will flow from point OO over conductor C, and the various instrumentalities associated therewith, to 30 wire 25, armature 21, wire 28, armature 29, wires 30 and 13, conductor B, and wires 9 and 10 back to secondary of T. It will be noted that relay E^1 no longer receives current because armature 19 is down, and hence, after a certain lapse of time, 35 relay E^1 becomes deenergized and drops armatures 24 and 27 thus opening the low impedance paths from C. Likewise relay D^1 will after a given period drop its armature 34, thereby rupturing the supply circuit to transformer T and 40 so rendering the system inoperative. Lights I^1 and I^2 will, of course, also have become extinguished.

If conductor B is open, say at U^1 , current will flow through both windings of relay G as before, 45 but not through winding RR of relay H. The armatures of relay H therefore drop and current will flow over conductor C from point OO, to wire 25, armature 24, wire 23, armature 22, wires 21 and 12 to A and thence back to secondary of 50 transformer T. Upon the expiration of the release period of relay E^1 , armatures 24 and 27 will drop thereby extinguishing lights I^1 and I^2 and causing deenergization of relay D^1 so that the latter drops its armature 34 and renders the system inoperative.

If conductor C is ruptured, say at U^2 , current at once ceases to flow therein, lights I^1 and I^2 are extinguished and relay D^1 drops armature 34, after a lapse of time, thereby opening the 60 circuit that supplies current to transformer T and so rendering the system inoperative.

If conductors A and C are short-circuited, say at U and U^2 , the current from secondary of 65 transformer T will not flow through winding PP of relay H but will cross over from A to C. Consequently armatures 19, 22 and 29 drop and, relay E^1 being slow in its release, the following circuit is established: From secondary of transformer T, by way of conductor A, short-circuit U— U^2 , conductor C, wire 25, armature 27, wire 28, armature 29, wires 30 and 13, conductor B, and wires 9 and 10 back to secondary of transformer T. Thus relay G is bridged by a very 70 75

low impedance path that does not include any rectifier, and consequently armature 32 drops thereby opening the supply circuit to transformer T, all relays drop and lights I¹ and I² are extinguished.

If a short-circuit occurs between conductors B and C, say at U¹ and U², then obviously winding RR of relay H will receive no current and armatures 19, 22 and 29 will drop. As long as relay E¹ remains energized and holds up its armatures, the following circuit will be established: from secondary of transformer T, over wire A, wires 12 and 21, armature 22, wire 23, armature 24, wire 25, conductor C, short-circuit U¹—U², conductor B, and wires 9 and 10 back to secondary of transformer T. Here again, a low impedance path devoid of rectifiers bridges relay G and consequently armature 32 drops and the system is rendered inoperative in the manner previously described.

If conductors A and B are short-circuited, say at U and U¹, relay G at once drops its armature 32 because said relay will be bridged by the short-circuit which would constitute a low impedance path, and the system is rendered inoperative.

If condensers C¹ or C² associated with relay G become short circuited, the relay winding which the particular condenser tunes to resonance will become detuned, and the current flowing in the winding is diminished to such an extent that armature 32 drops and the system is rendered inoperative as before. If condensers C³ or C⁴ associated with relay H is short circuited then armatures 19, 22 and 29 drop and the following circuit is established: From secondary of transformer T over conductor A, wires 12 and 21, armature 22, wire 23, armature 24, wire 25, armature 21, wire 28, armature 29, wires 30 and 13, conductor B and wires 9 and 10 back to secondary of T. Armature 32 therefore drops with the result previously described.

If there be an open circuit on any of the condensers C¹, C², C³ and C⁴, then the relay winding with which the particular condenser is associated becomes deenergized and the armature controlled by such relay drops thereby rendering the system inoperative in the manner previously set forth.

It will be apparent that, in the case of the arrangement of Fig. 2, signaling can likewise be carried on by means of keys X, Y because both relays D¹ and E¹ are of the slow-release type.

I claim:

1. A control system including: two line conductors extending from one station to another, a cross conductor at each station connecting the two line conductors, a third line conductor extending from a point having a certain potential on one cross conductor to a point having a different potential on the other cross conductor to thereby in effect constitute the bridge element of an unbalanced Wheatstone bridge, a circuit including a current source to supply current to said line conductors, two relays the winding of one of which is included in one of the cross conductors and the winding of the other of which is included in the third line conductor, and armatures operated by said relays for disconnecting said circuit from said line conductors when either one or both of said relays are deenergized.

2. A control system including: two line conductors extending from one station to another, means for creating a difference of potential across said conductors, two relays, each having two windings of unequal impedance, the two windings

of one relay being connected in series in one relative arrangement across the two line conductors at one station and the two windings of the other relay being connected in series in the other relative arrangement across the two line conductors at the other station, to thereby create points of unequal potential in the two relays intermediate the two windings, a third line conductor extending from a point intermediate the two windings of one relay to a point intermediate the two windings of the other relay, indication means interposed in the third line conductor controlled by the flow of current in said third line conductor to denote the integrity or lack of integrity of said line conductors, and armatures controlled by said relays operative to disconnect said potential creating means from said line conductors when either one or both of said relays are deenergized.

3. A control system including: two line conductors extending from one station to another, means for creating a difference of potential across said conductors, two relays, each having two windings of unequal impedance, the two windings of one relay being connected in series in one relative arrangement across the two line conductors at one station and the two windings of the other relay being connected in series in the other relative arrangement across the two line conductors at the other station, to thereby create points of unequal potential in the two relays intermediate the two windings, a third line conductor extending from a point intermediate the two windings of one relay to a point intermediate the two windings of the other relay, a relay in the third line conductor, and indication means controlled by said relays and effective for indicating integrity of said line conductors when and only when all three relays are energized.

4. A control system including: two line conductors extending from one station to another, means for creating a difference of potential across said conductors, two relays, each having two windings of unequal impedance, the two windings of one relay being connected in series in one relative arrangement across the two line conductors at one station and the two windings of the other relay being connected in series in the other relative arrangement across the two line conductors at the other station, to thereby create points of unequal potential in the two relays intermediate the two windings, a third line conductor extending from a point intermediate the two windings of one relay to a point intermediate the two windings of the other relay, an armature controlled by one of the relays for disconnecting said third line conductor when said one relay is deenergized, and an armature controlled by the other of said relays for disconnecting said potential creating means when said other relay is deenergized.

5. A control system including: two line conductors extending from one station to another, means for creating a difference of potential across said conductors, two relays, each having two windings of unequal impedance, the two windings of one relay being connected in series in one relative arrangement across the two line conductors at one station and the two windings of the other relay being connected in series in the other relative arrangement across the two line conductors at the other station, to thereby create points of unequal potential in the two relays intermediate the two windings, a third line conductor extending from a point intermediate the two windings of one relay to a point intermediate the two windings of the other relay.

termidate the two windings of the other relay, indication means interposed in the third line conductor controlled by the flow of current in the third line conductor to denote the integrity or lack of integrity of the line conductors, an armature controlled by one of the relays for disconnecting said third line conductor when said one relay is deenergized, and an armature controlled by the other of said relays for disconnecting said potential creating means when said other relay is deenergized.

6. A control system including: two line conductors extending from one station to another, means for creating a difference of potential across said conductors, two relays, each having two windings of unequal impedance, the two windings of one relay, being connected in series in one relative arrangement across the two line conductors at one station and the two windings of the other relay being connected in series in the other relative arrangement across the two line conductors at the other station, to thereby create points of unequal potential in the two relays intermediate the two windings, a third line conductor extending from a point intermediate the two windings of one relay to a point intermediate the two windings of the other relay, a circuit closing armature interposed in the third line conductor, controlled by one of the relays and held closed only so long as both of the windings of said relay are effectively energized, and a circuit closing armature controlled by the other of said relays for connecting said potential creating means to said two line conductors and held closed only so long as both of the windings of said other relay are effectively energized.

7. A control system including: two line conductors extending from one station to another, means for creating a difference of potential across said conductors, two relays, each having two windings of unequal impedance, the two windings of one relay being connected in series in one relative arrangement across the two line conductors at one station and the two windings of the other relay being connected in series in the other relative arrangement across the two line conductors at the other station, to thereby

create points of unequal potential in the two relays intermediate the two windings, a third line conductor extending from a point intermediate the two windings of one relay to a point intermediate the two windings of the other relay, a relay in the third line conductor, and armatures controlled by said relays operative to disconnect said means for creating a difference of potential between said line conductors when any one or all three of said relays are deenergized.

8. A control system including: two line conductors extending from one station to another, means for creating a difference of potential across said conductors, two relays, each having two windings of unequal impedance, the two windings of one relay being connected in series in one relative arrangement across the two line conductors at one station and the two windings of the other relay being connected in series in the other relative arrangement across the two line conductors at the other station, to thereby create points of unequal potential in the two relays intermediate the two windings, a third line conductor extending from a point intermediate the two windings of one relay to a point intermediate the two windings of the other relay, a low impedance path connected to the third line conductor and bridging the windings of one of the relays, circuit closing means in said path held in open position as long as the windings of the relay so bridged are energized, a relay in the third line conductor, circuit closing means in said path held in closed position as long as the relay in the third line conductor remains energized, a circuit closing armature in the third line conductor held in closed position as long as the windings of the relay that is bridged by the low impedance path remains energized, indicating means interposed in the third line conductor responsive to the current flow therein to denote the integrity or lack of integrity of said line conductors, and a circuit closing armature held in a closed position as long as the winding of the other of the first two mentioned relays remains energized to connect the potential creating means to said two line conductors.

RALPH KENT CROOKS.
